STETHOSCOPE

Donald E. Lewis, Arcadia, Calif., and Peter D. George, Easton, and Joseph A. Amarante, North Haven, Conn., assignors to Corometrics Medical Systems, Inc., North Haven, Conn.

Filed Feb. 18, 1970, Ser. No. 21,487

Term of patent 14 years

Int. Cl. D24—02
U.S. Cl. D83—12

FIG. 1 is a side elevational view of a stethoscope embodying our new design, the opposite side elevational view being identical;

FIG. 2 is a front elevational view of the stethoscope shown in FIG. 1;

FIG. 3 is a rear elevational view of the stethoscope shown in FIG. 1;

FIG. 4 is a top plan view of the stethoscope shown in FIG. 1;

FIG. 5 is a bottom plan view of the stethoscope shown in FIG. 1;

FIG. 6 is a cross-sectional view taken along the line 6—6 of FIG. 2;

FIG. 7 is a cross-sectional view taken along the line 7—7 of FIG. 1; and

FIG. 8 is a cross-sectional view taken along the line 8—8 of FIG. 1.

We claim:

The ornamental design for a stethoscope, as shown and described herein.
